(57) **CLAIM**

The ornamental design for a patterned hair removal device, as shown and described.

DESCRIPTION

FIG. 1 is a front perspective view of a first embodiment of a patterned hair removal device of the present invention showing our new design;

FIG. 2 is a front elevation view thereof;

FIG. 3 is a back elevation view thereof;

FIG. 4 is a side elevation view thereof;

FIG. 5 is a top plan view thereof;

FIG. 6 is a bottom plan view thereof;

FIG. 7 is a front perspective view of a second embodiment of a patterned hair removal device of the present invention showing our new design;

FIG. 8 is a front elevation view thereof;

FIG. 9 is a back elevation view thereof;

FIG. 10 is a side elevation view thereof;

FIG. 11 is a top plan view thereof;

FIG. 12 is a bottom plan view thereof;

FIG. 13 is a front perspective view of a third embodiment of a patterned hair removal device of the present invention showing our new design;

FIG. 14 is a front elevation view thereof;

FIG. 15 is a back elevation view thereof;

FIG. 16 is a side elevation view thereof;

FIG. 17 is a top plan view thereof;

FIG. 18 is a bottom plan view thereof;

(Continued)

FIG. 19 is a front perspective view of a fourth embodiment of a patterned hair removal device of the present invention showing our new design;

FIG. 20 is a front elevation view thereof;

FIG. 21 is a back elevation view thereof;

FIG. 22 is a side elevation view thereof;

FIG. 23 is a top plan view thereof; and,

FIG. 24 is a bottom plan view thereof.

The broken lines illustrate portions of the patterned hair removal device and form no part of the claimed design.

The stippling shown herein depicts a gradation in color from areas of dense stippling to areas of less dense stippling.
